(57) **CLAIM**

The ornamental design for a wrist weight, as shown and described.

DESCRIPTION

FIG. 1 is a front, top perspective view of a first embodiment of a wrist weight, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another perspective view of the wrist weight, shown in an alternative position;

FIG. 10 is a front, top perspective view of a second embodiment of the wrist weight; the second embodiment only differs from the first embodiment in the broken line feature on the surface of each segment of the wrist weight;

FIG. 11 is another perspective view thereof, shown in an alternative position; and,

FIG. 12 is an enlarged view of detail "12" identified in FIG. 2.

The dashed lines in the figures illustrate portions of the wrist weight that form no part of the claimed design. The dash dot dash lines in FIGS. 2 and 12 are for the purpose of illustrating the enlarged view indicators and form no part of the claimed design.
